UNITED STATES PATENT OFFICE.

WILLIAM HENRY CLING, OF CHARLESTON, SOUTH CAROLINA.

BED.

No. 926,854.

Specification of Letters Patent.

Patented July 6, 1909.

Application filed June 18, 1908. Serial No. 439,105.

To all whom it may concern:

Be it known that I, WILLIAM H. CLING, a citizen of the United States, and a resident of Charleston, in the county of Charleston and 5 State of South Carolina, have invented certain new and useful Improvements in Beds, of which the following is a specification.

This invention is an improvement in invalid beds, and consists in certain novel constructions and combinations of parts as will 10 be hereinafter described and claimed.

In the drawings, Figure 1 is a top plan view of a bed embodying my invention. Fig. 2 is a vertical longitudinal section thereof on 15 about line 2—2 of Fig. 1. Fig. 3 is a side view of the bed, the head section being raised. Fig. 4 is a sectional view of the bed, the head section being raised, and the foot section being lowered. Fig. 5 is a cross section 20 of the bed, and Fig. 6 is a detail perspective view showing one of the box supporting cross bars.

In the construction shown the bed comprises a middle or main section A, a head section B, pivoted at B' adjacent to the main section, and a foot section C, pivoted at C' adjacent to the main section, so the head and foot sections may be adjusted between the different positions shown in the drawings.

The head section B, is provided adjacent to its pivot B' with a depending arm B², and the section C has a depending arm C², and these arms B² and C² are connected by links B³ and C³ with eccentrics D and E on cross 30 shafts D' and E', the links having straps B⁴ and C⁴ encircling their respective eccentrics D and E as shown. The shafts D' and E' are journaled in brackets D² and E² depending from the bed frame, and by the turning 35 of the eccentrics D and E which may be effected by suitable hand cranks F, see Fig. 1, fitting detachably in sockets in the shafts D' and E', the sections B and C may be adjusted to any desired position as will be 40 understood from the accompanying drawings.

The bed bottom it will be noticed may be of any suitable form of spring G carried by the sections B and C and extending straight 45 when the parts are in the position shown in Fig. 2, but manifestly when the sections B and C or either of them is adjusted out of alignment with the section A, means should be provided to operate upon this continuous bed bottom G. To this end I provide a tension device in connection with the head and

foot sections. To this end the foot section C is provided with an arm C⁵ extending in advance of its pivot C' so that when the foot section is lowered to the position shown in Fig. 4, the said arm will put the bed bottom under tension.

In connection with the head section B, I provide brace bars B⁵ connected at one end with crank arms C⁶, on the shaft E' and connected at their other or front ends by a cross rod B⁶, which is connected by any suitable number of coiled springs B⁷ with the bed bottom G at a point approximately over the pivot B' of the head section B. By this construction when the head section is raised and the foot section is in its normal outstretched position shown in Fig. 3, the slack in the spring bed bottom will be taken up by the spiral springs B⁷, and when the foot section is lowered to the position shown in Fig. 4, this will operate through the movement of the braces to remove the tension of the springs B⁷ in taking up the slack.

A box or support H is carried at one side 80 by swinging hangers I, and at its other side by swinging carriers J. The swinging hangers I may be secured to the cross rods K in any suitable manner and the swinging hangers or carriers J are pivoted at their upper 85 ends J' to the slides J² movable along the rods E' and D' by any suitable means, such for instance as a chain leading to the side of the bed so the slides J² may be moved along the rods E' and D' to raise and lower the 90 box H. The box H may be utilized as a commode a suitable opening being provided in the main section A to permit its use for such purpose.

I claim—

1. A bed substantially as herein described consisting of an intermediate or main section, head and foot sections pivoted adjacent to the intermediate or main section, and provided at their pivoted ends with depending arms, eccentrics, and links connected with the arms of their respective sections and having straps encircling their respective eccentrics, a crank arm in connection with the eccentrics of the foot section, brace bars secured at one end to the said crank arms, a bed bottom, and coiled springs between the other ends of the brace bars and the bed bottom substantially as set forth.

2. A bed having a pivoted head section, an eccentric disk, a link connected with the said section and having a strap on the eccen-

- tric disk whereby it may be operated to adjust the section to different positions, substantially as set forth.
3. A bed having a foot section, an eccentric disk, a link connected with the said section and having a strap receiving the disk whereby the latter may be operated to tilt the foot section to any desired angle.
4. The combination of a bed bottom, and a pivoted foot section having in advance of its pivot a projecting arm movable with the foot section and adapted to operate below the bed bottom and to take up slack therein when the foot section is lowered.
5. The combination in a bed, of a main section, head and foot sections pivoted adjacent to the main section and having at their movable ends upwardly projecting portions for the connection of a bed bottom, a bed bottom between said portions, an arm movable with the foot section and extending from the said section in advance of the pivot thereof and projecting below the bed bottom when the foot section is lowered, and springs connected with the bed bottom adjacent to the pivoted end of the head section for taking up slack in the bed bottom when the head section is raised, substantially as set forth.
6. The combination in a bed of a box or support, swinging hangers carrying one side of said box, swinging hangers carrying at one end the other side of the box, slides for the other ends of the latter swinging hangers, and means along which said slides may be moved to raise and lower the box or support substantially as set forth.
7. The combination with cross rods and slides movable along the same, of hangers connected at one end with said slides and movable at such ends with the slides along the cross rods, and a box or support carried by the other ends of the said hangers, substantially as set forth.
8. A bed comprising a main section, head and foot sections, a bed bottom, devices adjacent to the pivot of the head section for taking up slack in the bottom, and means for operating said take up devices from the foot section when the latter is lowered.
9. The improvement in beds herein described, comprising a bed bottom, a main section, a pivoted head section, a pivoted foot section having beyond its pivot a projecting portion adapted to be operated below the bed bottom when the pivoted foot section is lowered, devices adjacent to the pivot of the head section for taking up slack in the bottom, and means for operating said take up devices from the foot section when the latter is lowered.

WILLIAM HENRY CLING.
